UNITED STATES PATENT OFFICE

LEANDER A. COGSWELL, OF MANCHESTER, NEW HAMPSHIRE, ASSIGNOR TO LACENE MANUFACTURING COMPANY, OF MANCHESTER, NEW HAMPSHIRE, A CORPORATION OF MAINE

GRADING, FLESHING, AND EVENING MACHINE

Application filed April 25, 1925. Serial No. 25,922.

In my application Serial No. 720,215, filed June 16, 1924, for a grading, fleshing and evening machine, I described a machine capable of fleshing and grading (as by marking) only blanks of a thickness grade between 5 predetermined upper and lower limits, and of grading (as by marking) without fleshing all blanks of a grade below the predetermined lower limit of thickness, and of evening all 10 blanks above the predetermined upper limit of thickness down to such predetermined upper limit, and grading them (as by marking).

There was no provision, however, in my 15 said former machine, for producing blanks in which the variation of thickness in different parts of each individual blank would be kept within predetermined limits, except as defined by said predetermined upper limit to which all blanks are to be evened down, 20 and no provision for producing blanks of different thickness grades in which the permissible variation in each blank would be kept within the same predetermined limits for different blanks of different thickness 25 grades.

For example, if the machine of my said former application is set to skive all blanks having spots or areas over 8 irons in thickness down to a maximum thickness of 8 irons, 30 a 4 iron blank (the grade of a blank is determined by its thickness measurement at the thinnest spot felt by the detector) may vary in thickness in different parts from 4 to 8 irons, i. e. a variation of 4 irons in the same 35 piece of stock; or a 6 iron blank may vary in different parts from 6 to 8 irons, i. e. a variation of 2 irons in the same piece of stock, and so on. That is, the possible variations in different blanks of different thickness grades 40 will all differ, and the upper limit of the permissible variation in any piece of stock irrespective of its grade will be set only by said predetermined upper limit to which all blanks are to be evened down.

45 For some purposes such variations in the thickness of different parts of a blank, and such lack of uniformity in the thickness variations of different blanks of different grades, are not objectionable; but for other purposes 50 they are.

For instance, a shoe manufacturer may wish to produce inner soles of different grades in which the maximum variation in thickness shall be the same for all blanks of whatever grade, or for all blanks which fall within 55 certain grades, and further he may wish that said maximum variation in thickness in any one sole shall not exceed 1 iron, or some other predetermined limit, notwithstanding the original piece of stock may have varied in 60 thickness in different parts very much more.

One principal object of the present invention is to devise a machine of the character referred to capable of accomplishing these 65 results.

An "iron", as the term is used in this art to designate a unit of thickness measurement, is $\frac{1}{16}$ inch.

Again, as a further refinement, the manufacturer may wish to provide for a maximum variation of one predetermined amount in soles of a grade above a specified grade or measurement, but to permit another and larger variation in thinner soles, i. e. soles 70 of a grade below said specified grade or measurement. Said specified grade measurement which constitutes the dividing line between the thicker class and the thinner class of blanks may be selected according to the 75 material of which the blanks are made, or the uses to which the finished blanks are to be put, or it might even be arbitrarily selected. Furthermore in the lower or thinner grades 80 of stock it may be desirable that the permissible variation in thickness should be increased progressively as the stock becomes 85 thinner. The reason why it may be desirable to permit greater variation in the thickness 90 of the lighter or thinner pieces of stock than in the heavier or thicker pieces of stock is that the thinner stock is usually of softer and looser texture and of inferior quality, and the more material skived off the more 95 flimsy it becomes. It may therefore be desirable to skive off from very thin pieces as little as is consistent with the uses to which they are to be put. In practice the uses of such thin or low grade stock may and often 100

do admit of considerably more variation in thickness than is consistent with the more exacting uses of the thicker and higher grades. It is therefore a further object of the invention to provide means to set one limit 5 to the maximum permissible variation of thickness in blanks of heavier or thicker grades, and a different limit to the maximum permissible variation in blanks of lighter or thinner grades, said different limit being 10 preferably progressively higher in proportion as the blanks are thinner, and further to provide that no fleshing shall be performed on those parts of the thinner blanks which 15 are below a predetermined thickness measurement.

Referring to the accompanying drawings which illustrate a preferred embodiment of the invention,

20 Fig. 1 is an end elevation of the rear or delivery end of the machine, corresponding to the view in Fig. 4 of my said application Serial No. 720,215;

25 Fig. 2 is an enlarged view partly in section of the upper part of Fig. 1;

Figs. 3, 4, 5, 6 and 7 illustrate various positions of the stepped wedge blocks or inclines presently to be described; and

30 Figs. 3^a, 4^a, 5^a, 6^a and 7^a illustrate in diagram the positions of the skiving rolls corresponding respectively to the positions of the wedge blocks shown in Figs. 3 to 7.

As the present invention is applicable particularly though not exclusively, to a machine of the kind shown in my said application Serial No. 720,215, I have adopted that type of machine for the purpose of illustration and have shown in the drawings only such parts of the machine as are necessary to an 35 understanding of the novel features of the present invention. For a description of the general construction and operation of the machine as a whole I refer to my said application Serial No. 720,215. For convenience of 40 reference also I will use the same reference numerals, so far as applicable, as used in my said former application.

The skiving and delivery rolls 16 and 17 and the skiving or splitting knife 18 may be 45 substantially the same as shown in my said former application; also the cross bar 54 and the journal boxes 55, 55 for the upper roll 16 and the cross bar 65 on the under side of the journal boxes 64, 64 of the lower roll 17; also 50 the springs 66 and supporting structure for the cross bar 65; also the slide bar 33 and the supplemental bar 51 with their respective stops and connections, and the fixed yoke 60 on top of the machine frame.

60 It will be understood that the slide bar 33 is adjusted endwise on the cross head of the machine frame in accordance with the thinness detections of the feeler rolls (not shown) at the front of the machine, and that said 65 slide 33 adjusts the grade marking wheel

(not shown) if used, and also the upper wedge blocks 50, 50 carried by slide 33, as explained in my said former application. The lower wedge blocks 53, 53 are fixed to the cross bar 54, which is carried by the journal boxes 70 of the upper skiving roll 16.

Two plungers 56, 56 extend downward through openings in the cross rail 57 of the machine frame and also through a slot 33' in the slide bar 33. These plungers 56 have collars or flanges 56' at the top to act as stops when they engage the cross rail 57. Two heavy springs 58, 58 press the plungers downward, and bear at their upper ends 75 against abutments 59, which are loose on bolts 100 and are adjustable by means of stop nuts 101 and lock nuts 102. The bolts 100 are threaded through yoke 60, and may be locked in their adjusted position by nuts 103. The lower ends of bolts 100 form abutments or stops for plungers 56 as hereinafter explained, and are normally spaced a predetermined distance according to the work required of the machine, say about 3 irons in the example presently to be given, from the top 80 surface of the plungers 56.

As in the machine of my said former application, the upper springs 58 are weaker than the lower springs 66 and will consequently yield in the operation of the machine to the 95 limit of movement of the plungers 56 before any compression of the lower springs 66 takes place.

The upper wedge blocks 50 are each made with the usual stepped incline 104, (see Figs. 3 to 7) the steps of which are one-half iron in height to conform to the usual standard of measurement and classification of the leather stock in terms of irons and half irons. At the top of the incline is a flat or horizontal surface 105 of a length equal to the length of the flat surface of two steps of the incline. A recess 106 is cut in the upper block, at the opposite end of the flat surface 105 to the incline, to form a clearance for the high point 100 of the opposite wedge block 53 in certain positions of the parts.

Each of the lower wedge blocks 53 also has a stepped incline 107 corresponding to the stepped inclines 104 of the upper blocks, and a flat horizontal surface 108 at the top of the incline, two steps long, like the flat surface 105. The lower blocks also have a recess 109 to receive the high point of the upper blocks 105 and to form an abutment therefor at a predetermined height. In order to be able to 115 vary this height a removable "shim" 110 is fitted into the shoulder formed by recess 109. By replacing the shim with another of 120 different thickness the height of the abutment surface may be varied.

Assume now, for the purpose of illustration, that all blanks of a predetermined upper grade, say those measuring 5 irons or 125 more at the thinnest spot, are to be fleshed and 130

are also to be so skived or evened as to keep the maximum variation in thickness in any one blank down to a predetermined amount, say 1 iron. Assume further that all blanks 5 below said assumed grade of 5 irons are to be skived or evened to keep the maximum variation in thickness in any one blank down to a different predetermined amount, which amount is greater than the variation permissible in the thicker blanks, and which amount 10 is to increase progressively as the blanks become thinner. And assume further that of all blanks below said assumed grade of 5 irons, those of a grade above a predetermined measurement, say $3\frac{1}{2}$ irons, are also to be fleshed, and those of the grade of $3\frac{1}{2}$ or less are not to be fleshed as to any areas measuring not 15 more than $3\frac{1}{2}$ irons.

It will be understood that all of the aforesaid assumed measurements are by way of example only and may be altered without departing from the principle of the invention.

To accomplish the objects stated, in the assumed example, the stop bolts 100 are adjusted and set so as to space their ends substantially 3 irons from the tops of plungers 56, and the shoulders 109 of the lower wedge blocks 53 are built up by "shims" 110 of such height that the abutment surfaces of 30 110 are $\frac{1}{2}$ iron below the flat top surfaces 108.

The machine is so adjusted and the wedge blocks are relatively so disposed that when a sole with the flesh on it measures or grades $3\frac{1}{2}$ irons in thickness at its thinnest spot as 35 determined by the detecting device, the upper wedge blocks will be adjusted through the usual setting mechanism which shifts the slide bar 33 to the position shown in Fig. 3, with the flat surfaces 105 of the upper blocks in the first position to the left of the flat surfaces 108 and opposite abutments 110 in the shoulders of the lower blocks. This 40 may be termed the first position.

The vertical space between the upper and 45 lower wedge blocks in the first position when no sole or blank is present, is such that when the upper skiving roll is lifted by a blank $3\frac{1}{2}$ irons thick, the abutment surfaces 110 of the lower blocks will just engage without pressure (or will just miss engaging) the flat surfaces 105 of the upper wedge blocks as 50 shown in Fig. 3, the upper roller 16 then being separated $3\frac{1}{2}$ irons from the lower roller 17 by the blank as shown in Fig. 3a. The edge of the fleshing knife 18 is usually 55 spaced about $\frac{1}{2}$ iron from the surface of the lower roller 17 so as to skive off $\frac{1}{2}$ iron from the flesh side of the blank when the fleshing action takes place; but in order to be 60 acted upon by the knife the blank must be held down under pressure from above against the lower roller 17 and knife 18. Consequently under the conditions stated with the parts in the first position any part of the blank 65 measuring not over $3\frac{1}{2}$ irons thick, not being

under pressure, will pass through the skiving mechanism without being cut. But if the blank measuring $3\frac{1}{2}$ irons at its thinnest spot has areas thicker than $3\frac{1}{2}$ irons, say $4\frac{1}{2}$ or 5 irons thick, the thicker areas will lift the roller 16 and with it the lower blocks 53, whose abutments 110 are now in engagement with the flat surfaces 105 of the upper blocks 50, against the pressure of springs 58, and such thicker areas now being held under yielding pressure against the lower roller and knife will be fleshed to the depth of $\frac{1}{2}$ iron, (that being the spacing between the edge of knife 18 and the roller 17) if the thicker areas are $\frac{1}{2}$ or more in excess of the assumed $3\frac{1}{2}$ iron thickness which is to be allowed to pass unskived, or will be fleshed down to said $3\frac{1}{2}$ iron thickness if the thicker areas are less than $\frac{1}{2}$ iron in excess of said $3\frac{1}{2}$ iron thickness. And in case any thicker spots exceed the said $3\frac{1}{2}$ iron thickness by more than the yielding limit of the plungers 56, which was assumed for illustration to be 3 irons, the plungers 56 will be stopped by the ends of the stop bolts 100 and thereafter such thicker areas will press the lower roller 17 downward against springs 66 and cause a thicker skiving to be cut off, thus insuring that the thickness of the thickest areas of the finished blank will not exceed said $3\frac{1}{2}$ irons by more than the amount determined by the extent of the yield of the plungers 56, that is, 3 irons. It will therefore be seen that any spot of the blank measuring only $3\frac{1}{2}$ irons in thickness will pass through the skiving mechanism without being cut, any area more than $3\frac{1}{2}$ irons thick and not more than $6\frac{1}{2}$ irons thick will be fleshed; and any spot more than $6\frac{1}{2}$ irons thick will be evened down to $6\frac{1}{2}$ irons.

If the detected grade of a blank is less than $3\frac{1}{2}$ irons the slide bar 33 will be shifted farther to the left (Fig. 2) by the detecting mechanism a distance equal to the width of one step of the stepped wedges for each half iron less in the detected thickness, with the result that the flat surfaces 105 of the upper wedge blocks will remain opposite the elongated abutment surfaces 110 of the lower wedge blocks, but said thinner stock will not lift the lower wedge blocks into engagement with the upper blocks unless and until a spot of $3\frac{1}{2}$ irons or more in thickness enters between the rollers. For areas more than $3\frac{1}{2}$ irons thick the action will be as described in connection with the $3\frac{1}{2}$ iron blank. Thus it will be seen that the thinner or lighter the grade of the blank the wider will be the range in the finished blank between the thinnest spot and the predetermined maximum thickness of the thickest spot. As already explained, in very thin blanks it is desirable not to skive off any material from areas of less than a predetermined thickness, ($3\frac{1}{2}$ irons in the assumed example) and although 130

as the blanks become thinner this results in a progressively greater variation between the thinnest spot and the predetermined maximum thickness of the thicker spots, such variation is permissible for most uses of the thinner and inferior grades, and no material is lost from those areas which are too thin and flimsy to be further weakened.

Referring now to the action of the machine on blanks of a detected grade of more than 3½ irons at the thinnest spot measured by the detecting device, a 4 iron blank will shift the slide bar 33 and the upper wedge blocks to the position shown in Fig. 4 with the right hand half of the flat surfaces 105 of the upper blocks opposite the left hand half of the flat surfaces 108 of the lower blocks. This may be termed the second position. When the blank 4 irons thick is between the skiving rollers, the upper roller will of course be lifted by the blank 4 irons from the lower roller; but as soon as the upper roller has been lifted 3 irons the flat surfaces 108 of the lower wedge blocks will engage the flat surfaces 105 of the upper wedge blocks and consequently the lifting of the upper roller for the remaining distance of 1 iron will be against the pressure of springs 58. Hence the blank will be under a pressure that may be termed 1 iron pressure, which is usually sufficient in material of that thickness to cause the blank to be fleshed. Thicker areas up to 6 irons, which is the limit of the yield of the upper roller, will similarly be fleshed, but any areas exceeding 6 irons in thickness will be evened down to 6 irons since the upper roller will be stopped by the stop bolts 100 at 6 irons separation from the lower roller and after that the lower roller will yield downwardly. Thus a 4 iron blank will be fleshed as to any area from 4 to 6 irons inclusive, and any area over 6 irons thick will be evened down to 6 irons, permitting a maximum variation in thickness of 2 irons; and the thicker the area being cut the greater the pressure on the blank.

Fig. 4^a represents diagrammatically the position of the skiving rollers for a 4 iron blank, corresponding to the position of the wedge blocks in Fig. 4; the solid line of upper roller 16 indicating a separation of 4 irons from the lower roller, the dotted line representing the position of the upper roller when the wedge blocks first engage at 3 irons separation, and the distance, 1 iron, between said two positions representing 1 iron pressure.

A 4½ iron blank will shift the slide bar 33 and the upper wedge blocks 50 to the position shown in Fig. 5 with the whole of the flat surfaces 105 of the upper blocks directly opposite the whole of the flat surfaces 108 of the lower blocks. This may be termed the third position. As before, the blocks will first engage when the rollers are separated 3 irons; but as the blank is a 4½ iron blank

there will now be exerted 1½ irons pressure on the blank when the roller is lifted the remaining 1½ irons distance by the 4½ iron blank. Thus a 4½ iron blank will be fleshed as to any area from 4½ to the maximum of 6 irons, a variation of 1½ irons, and any area over 6 irons thick will be evened down to 6 irons, with increasing pressure the thicker the area.

Fig. 5^a represents diagrammatically the position of the rollers corresponding to the position of the wedge blocks in Fig. 5, the solid line as before indicating the elevation of the roller caused by the blank (4½ irons), the dotted line indicating the position at the first engagement of the wedge blocks (3 irons) and the difference between them indicating the pressure of 1½ irons. As the blank is a little thicker than in the previous position a little more pressure is required to insure the proper skiving, and is obtained as just described.

A 5 iron blank will shift the slide 33 and the upper wedge blocks to the position shown in Fig. 6 with the left hand half of the flat surfaces 105 of the upper wedge blocks opposite the right hand half of the flat surfaces 108 of the lower wedge blocks. This may be termed the fourth position. As the blank is a 5 iron blank, and as the wedge blocks engage at a 3 iron separation of the rollers, we now have a 2 iron pressure exerted on the blank by the springs 58. Thus a 5 iron blank will be fleshed as to any area from 5 to the maximum of 6 irons, a thickness variation of 1 iron, and any area over 6 irons thick will be evened down to 6 irons, with increasing pressure the thicker the area.

Fig. 6^a, as before, is a diagram of the position of the rollers corresponding to the position of the wedge blocks of Fig. 6, the solid line representing the elevation of the upper roller by the blank (5 irons), the dotted line representing the position of the roller at the first engagement of the wedge blocks (3 irons) and the difference between them representing the pressure (2 irons).

A 5½ iron blank will shift the slide 33 and the upper wedge blocks to the position shown in Fig. 7 with the flat surfaces 105 of the upper blocks opposite the first steps of the lower blocks, and the first steps of the upper blocks opposite the flat surfaces 108 of the lower blocks. This may be termed the fifth position. As already stated the steps of the wedge blocks are ½ iron high. Hence the wedge blocks will not engage until the upper roller has been lifted by the stock 3½ irons above the lower roller, and in lifting the roller the remaining 2 irons the 5½ iron blank will be placed under 2 irons pressure as in the fourth position; and as the upper wedge blocks may still yield one more iron before being arrested by the stop bolts 100, the maximum thickness to which the thicker areas will

be skived or evened down is $6\frac{1}{2}$ irons, thus maintaining the maximum variation in thickness at 1 iron.

Fig. 7^a, as before, is a diagram of the position of the rollers corresponding to the position of the wedge blocks of Fig. 7, the solid line representing the elevation of the roller 16 by the blank ($5\frac{1}{2}$ irons), the dotted line representing the position of the roller at the first engagement of the wedge blocks (now $3\frac{1}{2}$ irons) and the difference between them representing the pressure (2 irons).

It is found in practice that 2 irons pressure with springs 58 of the proper stiffness is usually sufficient for even the heaviest stock.

Thicker blanks than $5\frac{1}{2}$ iron blanks will position the slide 33 to the right, one step for each half iron increase in the detected thickness of the blank, and as the wedge blocks thus "step down" $\frac{1}{2}$ iron for each $\frac{1}{2}$ iron increase in thickness of the blank, the separation of the rollers before the wedge blocks come into engagement will correspondingly increase $\frac{1}{2}$ iron for each increase of $\frac{1}{2}$ iron in the thickness of the blank. Therefore there will never be more than 2 irons pressure exerted on the blank by the springs 58, and there never will be more than 1 iron variation between the thinnest and thickest spot in the finished blank. For example, a 6 iron blank will step the wedge blocks down one step farther; therefore pressure will remain the same and the separation of the rollers before the upper wedge blocks are stopped by bolts 100 will be $\frac{1}{2}$ iron greater than in the fifth position, or 7 irons. Hence from the fourth position, Fig. 6, upward the action of the skiving mechanism will be the same in respect to pressure and maximum permissible variation in thickness on all blanks irrespective of their grade, at least until further upward movement of the upper roll is arrested by the adjustable stops 62, 62, which are mounted on the ends of cross bar 54. The stops 62 limit the upward movement of roll 16 by abutting against the under side of slide 33, or preferably against hardened plates on the under side of slide 33, when slide 33 is shifted to the right far enough to separate the wedge blocks 50 and 53 more than a predetermined distance.

Although for the purposes of illustration I have adopted one iron as the maximum permissible variation in thickness in any given piece of stock of the thicker grades, it will be understood that if it is desired to permit a maximum thickness variation of a greater or less amount than one iron the bolts 100 may be set to provide a greater or less clearance between the ends of the bolts and the tops of plungers 56.

It will also be understood that by altering the normal separation of the wedge blocks when no blank is between the rollers, and consequently altering the extent of separation of the rollers permitted before the wedge

blocks come into contact, the upper limit of grade of the blanks which are to pass through unskived may be altered, also the pressures exerted on the upper roller after the wedge blocks engage one another. Also the abutment surfaces of the wedge blocks formed by the shims 110 may be raised or lowered by substituting shims of different thickness, or by adding or subtracting one or more shims of uniform thickness with a corresponding change in the measurements of the resulting blanks. Many objects of the invention may be realized if the abutment surface of 110 is on the same level with the flat surface 108. In fact all of the aforesaid illustrative measurements may be varied without departing from the principle of the invention.

I claim:

1. A machine of the kind described comprising a grade detecting device, a skiving knife and two opposed blank engaging members of which one at least is movable toward and from the other, an abutment carried by said movable blank engaging member, a co-acting, adjustable, yielding abutment adapted to respond to the grade detecting device, and a stop for the adjustable abutment to limit the yielding movement thereof.

2. A machine of the kind described comprising a detecting device, skiving mechanism for skiving blanks of different grades, and means responsive to the detecting device for controlling the skiving mechanism adapted to cause the skiving mechanism to confine the variation in thickness in different parts of the same blank within predetermined limits.

3. A machine of the kind described comprising skiving mechanism for skiving blanks of different grades, and means for controlling the skiving mechanism adapted to cause the skiving mechanism to flesh all blanks whose grade is within predetermined maximum and minimum limits of thickness, and to even blanks of different grades down to the same predetermined maximum limit of thickness in excess of their respective grades.

4. A machine of the kind described comprising skiving mechanism adapted to flesh all blanks whose grade is within predetermined maximum and minimum limits of thickness and to even any blanks above the predetermined maximum limit down to the predetermined maximum limit, and other means adapted to cause the skiving mechanism to even blanks of certain lower grades down to another predetermined upper limit less than the first mentioned predetermined maximum limit.

5. A machine of the kind described comprising a grade detecting device, a skiving knife and two opposed blank engaging members of which one at least is movable toward and from the other, an abutment carried by said movable blank engaging member, a co-acting, adjustable, yielding abutment adapt-

ed to respond to the grade detecting device, and an adjustable stop for the adjustable abutment to limit and vary the yielding movement thereof.

5. 6. A machine of the kind described comprising a detecting device, skiving mechanism for skiving blanks of different grades, and adjustable means responsive to the detecting device for controlling the skiving mechanism adapted to cause the skiving mechanism to confine the variation in thickness in different parts of the same blank within predetermined but variable limits.

7. A machine of the kind described comprising skiving mechanism including a skiving knife and two opposed blank engaging members movable toward and from each other, an abutment carried by one of said blank engaging members and a co-acting adjustable abutment adapted to respond to a grade detecting device, means to exert yielding pressure on said adjustable abutment and consequently on the latter blank engaging member when said abutments are in engagement, a stop for the adjustable abutment to limit the yielding movement thereof, and means to exert opposed and greater yielding pressure on the other blank engaging member.

30. 8. A machine of the kind described comprising skiving mechanism including a skiving knife and two opposed blank engaging members movable toward and from each other, an abutment carried by one of said blank engaging members and a co-acting adjustable abutment adapted to respond to a grade detecting device, means to exert yielding pressure on said adjustable abutment and consequently on the latter blank engaging member when said abutments are in engagement, an adjustable stop for the adjustable abutment to limit and vary the yielding movement thereof, and means to exert opposed and greater yielding pressure on the other blank engaging member.

45. 9. A machine of the kind described comprising skiving mechanism including a skiving knife and two opposed blank engaging members movable toward and from each other, a wedge-like abutment carried by one of said blank engaging members, an adjustable slide bar adapted to respond to a grade detecting device, a co-acting wedge-like abutment carried by and movable upon said slide bar, means to exert yielding pressure on said latter abutment and consequently on the latter blank engaging member when said abutments are in engagement, a stop for the last named abutment to limit the yielding movement thereof, and means to exert opposed and greater yielding pressure on the other blank engaging member.

60. 10. A machine of the kind described comprising skiving mechanism including a skiving knife and two opposed blank engaging

members movable toward and from each other, a wedge-like abutment carried by one of said blank engaging members, an adjustable slide bar adapted to respond to a grade detecting device, a co-acting wedge-like abutment carried by and movable upon said slide bar, means to exert yielding pressure on said latter abutment and consequently on the latter blank engaging member when said abutments are in engagement, an adjustable stop for the last named abutment to limit and vary the yielding movement thereof, and means to exert opposed and greater yielding pressure on the other blank engaging member. 70

11. A machine of the kind described comprising skiving mechanism including a skiving knife and two opposed blank engaging rollers movable toward and from each other, an adjustable slide bar adapted to respond to a grade detecting device, a wedge bar carried by the slide bar and vertically movable thereon between the slide bar and the upper roller, wedge-like abutments on the wedge bar and co-acting wedge-like abutments carried by the upper roller, one or more spring pressed members adapted to exert yielding pressure on the wedge bar and consequently on the upper roller, a stop to engage said spring pressed members and to limit the upward movement thereof, and means to exert opposed and greater yielding pressure on the lower roller. 80

12. A machine of the kind described comprising skiving mechanism including a skiving knife and two opposed blank engaging rollers movable toward and from each other, an adjustable slide bar adapted to respond to a grade detecting device, a wedge bar carried by the slide bar and vertically movable thereon between the slide bar and the upper roller, wedge-like abutments on the wedge bar, and co-acting wedge-like abutments carried by the upper roller, one or more spring pressed plungers extending through slots in the slide bar adapted to exert yielding pressure on the wedge bar and consequently on the upper roller, adjustable stop bolts adapted to engage the tops of said plungers to limit their upward movement, and means to exert opposed and greater yielding pressure on the lower roller. 90

13. A machine of the kind described comprising skiving mechanism including relatively movable upper and lower blank engaging members and a skiving knife, a wedge block carried by the upper blank engaging member and a co-acting adjustable wedge block for controlling the extent of separation of the upper from the lower blank engaging member, each wedge block having a flat horizontal top surface and a stepped incline at one side of said flat top, and one at least of said blocks having a shoulder at the other side of said flat top adapted to form an abutment for the flat top surface of the opposed wedge 110

block in a certain relative position of adjustment of the blocks.

14. A machine of the kind described comprising skiving mechanism including relatively movable upper and lower blank engaging members and a skiving knife, a wedge block carried by the upper blank engaging member and a co-acting adjustable wedge block for controlling the extent of separation of the upper from the lower blank engaging member, each wedge block having a flat horizontal top surface and a stepped incline at one side of said flat top, and one at least of said blocks having a horizontal shoulder at the other side of said flat top of such length as to form an abutment for the flat top surface of the opposed wedge block in a number of different relative positions of adjustment of the blocks.

15. A machine of the kind described comprising skiving mechanism including relatively movable upper and lower blank engaging members and a skiving knife, a wedge block carried by the upper blank engaging member and a co-acting adjustable wedge block for controlling the extent of separation of the upper from the lower blank engaging member, each wedge block having a flat horizontal top surface and a stepped incline at one side of said flat top, and one at least of said blocks having a horizontal shoulder at the other side of said flat top, and means to vary the height of said shoulder with relation to the flat top surface.

Signed by me at Boston, Massachusetts, this
35 twenty-second day of April, 1925.

LEANDER A. COGSWELL.
